COMPRESSOR OR PUMP

Harvey W. Bell, Yonkers, N. Y.

Application October 20, 1945, Serial No. 623,584

10 Claims. (Cl. 230—25)

1

This invention relates to compressors or pumps, and more particularly to a mechanism for varying their effective volumetric displacement or capacity.

It is in the nature of an improvement on the control mechanism described in my pending application Serial No. 559,361, filed October 19, 1944, now Patent Number 2,453,402, granted November 9, 1948.

In accordance with the invention described in said co-pending application, the cylinder of the compressor, whether it is of the single stage or multi-stage type, has an unloading valve which is positively maintained by a mechanical device in open position from the beginning of the compression stroke to a selected phase of said stroke prior to the opening of the discharge or delivery valve. This unloading valve may be the only inlet suction valve of the cylinder, or may be provided in addition to the ordinary inlet valve. While this unloading valve is open, air cannot be compressed in the cylinder and compression cannot begin until this valve is closed. This valve is initially opened during the final stages of the suction stroke, and is maintained open during the initial stages of the compression stroke, according to the setting of the valve control means. Means are provided for adjusting the phasing of the opening and closing of the unloading valve with respect to the stroke cycle of the piston. This adjustment is desirably so effected that the point in the suction stroke when the valve opens (as measured from the end of the suction stroke) corresponds to the phase in the compression stroke when said valve closes (as measured from the beginning of the compression stroke). For example, when the compressor is running with its displacement 100% effective, there is no mechanical opening or closing of the unloading valve; at 50% displacement, it would be opened approximately at midsection of the suction stroke if suction has not previously opened it and closed at midsection of the compression stroke; at one-third capacity, the unloading valve is opened during the suction stroke after the piston has traveled approximately one-third of said stroke, and is closed after traveling two-thirds of its compression stroke; and at zero displacement, it is open throughout the whole of the suction and compression strokes.

The unloading valve is so operated that, with any adjustment of its control, it remains closed during the suction stroke until the pressure of the air in the cylinder is less than the pressure of the air in the inlet pipe. Therefore, at the

2

end of the compression stroke, any compressed air in the clearance space will be reexpanded against the piston, and will not be released through the unloading valve. A substantial amount of the work of compressing this air in the clearance space is thereby returned to the piston and will not be lost.

With the control mechanism described in this said co-pending application, the unloading valve is operated by a rotating cam driven by the main crankshaft. This cam is of such contour that it is relatively difficult to fashion and relatively expensive.

It is an object of the present invention to provide a valve control mechanism which is simpler and less expensive than the one shown in the said co-pending application.

The action of the unloading valve in the present form of embodiment of compressor is exactly the same. But an oscillating instead of rotating cam is employed to operate the valve. The valve control cam of the present invention normally oscillates through an angle of approximately 30°, but the portion of its circumference in contact with the valve actuating roller may be shifted. This is accomplished by means of a control lever which serves to move the fulcrum of the mechanism for oscillating the cam. In one extreme position of the control lever the valve is held open continuously, while in another it is not held open at all, and in between it is held open during varying first portions of the compression strokes of the piston.

For other objects and for a better understanding of the invention, reference may be had to the following detailed description taken in connection with the accompanying drawing, in which

Fig. 1 is an end elevational view of the compressor having the special unloading valve and with the valve gear operating mechanism of the present invention directed to operate this valve;

Fig. 2 is a side elevational view of the compressor and valve mechanism shown in Fig. 1;

Fig. 3 is a fragmentary view partly in longitudinal section taken on the line 3—3 of Fig. 1;

Fig. 4 is an enlarged cross-sectional view taken in a horizontal plane through the top of the compressor, as at line 4—4 of Fig. 1 and illustrating the various valve arrangements associated with the compressor;

Figs. 5 and 6 are also diagrammatic illustrations of the valve gear mechanism where the oscillating cam has been moved to a position to effect automatically the opening and closing of

the special valve, the oscillating cam being shown respectively at different ends of its stroke; and

Figs. 7 and 8 are respectively diagrammatic illustrations of the valve gear mechanism showing the relative position of the parts where the cam has been moved to a position where the compressor operates at its maximum capacity and where the cam has been adjusted to a position where the valve is left open continuously and the compressor reduced to zero capacity.

Referring now to Figs. 1 to 4 there is shown a compressor 15 having an air-cooled cylinder 16 connected at its base by means of bolts 17 to a crankcase 18. Extending through the ends of the crankcase is a crank shaft 21 having a fly-wheel 21a and adapted to operate a connecting rod 22 and a piston 23 within the cylinder 16. The upper end of the cylinder 16 is closed by a water cooled cover 24, which may be like that shown in my application No. 559,361 having a portion 25 extending down into the cylinder chamber. Inlet and outlet water pipes 26 and 27 connect with the water cooled head 24 to supply water thereto and to discharge the heated cooling water.

Referring particularly to Fig. 4 there are provided on the cylinder 16 inlet and outlet ports 28 and 29. Contained within the inlet port 28 is an automatic suction valve mechanism 31 through which the fluid being supplied to the cylinder is controlled. As the piston makes a suction stroke the valve element 33 of this mechanism is opened away from the passages 34 against the action of springs 35, only one of which is shown. The inlet port 28 receives the gas to be compressed from an intake pipe 36 bolted to the cylinder 16 by means of bolts 37. By the same bolt means 37, the valve mechanism 31 is supported within the inlet and in axial alignment with an extension 38 of the inlet port. The air entering the port 28 can pass about the cylinder 16 through a passageway 39 in which a control valve 41 for unloading the compressor is disposed. The valve 41 is operable to and from a seat portion 42 to permit the entrance and exit of the fluid to and from the passage 39. The function of this valve is described in my co-pending application, but will be further described herein when detailed description is being made of the mechanism for operating this valve.

At a 90° angle from the inlet valve mechanism 31 and diametrically opposed to the special valve 41 is the outlet port 29 in which is disposed an automatic exhaust valve mechanism 43, which includes a valve plate 44 cooperating with exhaust passages 45 and so retained as to close off the same by means of springs 46, only one of which is shown. The valve mechanism 43 is supported by the same bolts 47 which connect the outlet pipe 48 to the cylinder 16 at the outlet port 29.

While the compressor is working at maximum capacity the operation of the inlet and outlet valve mechanisms is entirely automatic and well understood in the art. The valve mechanism 31 is opened during the suction stroke of the piston 23 to suck in air or other fluid from the inlet pipe 36 and closed during the compression or up-stroke of the piston 23, to exhaust the compressed air or other gas through the outlet valve mechanism 43. Both of these valve mechanisms are of the one way type.

The special valve 41 has a valve stem 51 which is retained in a valve supporting cage 52. This cage 52 has radially extending flanges 53 by which the cage is connected and retained in its proper

position within an opening 54 in the cylinder 16. The valve stem 51 when the valve 41 is closed, extends forwardly for some distance beyond the flange 53. It is urged to this position by a valve spring 54' operating between a washer 55 fixed on the end of the valve stem and the rear portion 56 of the valve cage 52. The front end of the valve stem 51 lies in a chamber 57 formed within a housing plate 53 connected to the cylinder 16 by means of bolts 59. The housing flanges 58' lie against the valve cage flange 53 and the bolts which retain this housing also retain the valve cage. Extending upwardly into the chamber 57 and adapted to engage the end of the valve stem to operate the valve is a tappet 61. This tappet is secured to a transversely extending shaft 62, and extends upwardly through the housing 58. The shaft 62 is supported by a laterally extending sleeve formation 63 thereof to a point where a roller 64 on an arm 65 engages an oscillating cam 66, located at one side of the compressor. A stuffing box including a gland 67 surrounds the shaft at the end of the sleeve formation 63 to retain a packing, not shown, within the sleeve 63.

The arm 65 has a bifurcated portion 68 connecting with the shaft 62. The arm may rotate on the shaft but is limited against leftward rotation by an adjustable take up screw 71 on an arm 72 fixed between the bifurcations of the portion 68 by a pin 73. By adjusting the screw 71 the position of the roller 64 relative to cam 66 is adjusted.

The cam 66 is pivoted on a stud 76 of an up-standing bracket 77 fixed to the bottom of the cylinder 16 by means of screws 78. The cam 66 is rocked on the pivot 76 by an eccentric 79 secured to one end of the crank shaft 21 by a key 81. Surrounding this eccentric is a device including two transversely-extending members 82 each having a circular opening 83 adapted to contain the eccentric 79. The members 82 carry a stud or fulcrum point 84 to which a link 85 is connected. This link 85 at its upper end connects with an arm 86 as indicated at 87 to rock the cam 66. In order to alter the position of the cam 66 so as to place the roller 64 either on a low portion 91 or on a high portion 92 of the cam 66 or in an intermediate position where the roller will be worked by sections of both the low and raised portions of the cam, there is provided a hand-adjusting mechanism 93 which includes a hand lever 94 pivoted on a portion 95 of the eccentric 79, the portion 95 being concentric with the crank shaft 21. The lever 94 is connected through links 96 with the forward ends of members 82 by a pin 96'. In order to retain the lever 94 in its adjusted position there is provided thereon a bolt 97 adapted to be slid through an arcuate slot 98 in a bracket 99 fixed to the gear case 18 by screws 101. The bolt 97 has a nut 102 for locking a hand lever 95 to the bracket 99 and in its adjusted position.

In the form of construction which is now preferred, the angle through which the eccentric 79 causes the cam 66 to oscillate is 30°. Adjustment of the lever 94 can cause the cam to move through an angle of 42°. Different portions of the circumference of the cam may thus be caused to contact the valve actuating roller 64 while the eccentric is oscillating the cam.

In Fig. 7 the control or hand lever 94 is shown as having been pulled to the left as far as it will go. As a result the members 82 are so positioned on the eccentric 79 that only the upper cam face

portion 91 of the cam engages roller 64 as the cam oscillates. The cam, therefore, does not lift the roller at any time during its oscillation, and the valve 41 is at no time held open mechanically so that the compressor operates at maximum capacity. If, now, the lever is moved to the right, as for example to the intermediate position shown in Figs. 5 and 6, the cam 91 will lift the roller 64 in the middle of the suction stroke and thus open valve 41 (if the same has not already been opened by the suction in the cylinder) and hold valve 41 open during the remainder of the suction stroke and during the first half of the compression stroke, by reason of the fact that during the oscillation of the cam the raised and lowered portions of the cam engage the roller successively. The compressor, therefore, operates at only partial capacity. It will thus be apparent that the further the lever 94 is moved to the right, the greater will be the portion of the compression stroke during which the valve is held open.

When the lever 94 is all the way to the right as in Fig. 8 the cam will oscillate without permitting the roller to run off the dwell or raised portion 92, so that the valve 41 is held open continuously and the capacity of the compressor is reduced to zero.

It will be noted that the construction of the control mechanism is such that the shaft of the compressor may be rotated in either direction with equal results for any position of the control lever. If desired, the valve gear may be enclosed and run in an oil bath, or it may be enclosed in a dustproof casing. It will also be noted that the form of construction of the valve mechanism is such that it lends itself to multi-cylinder compressors, and that it may readily be balanced.

As previously noted, as far as certain aspects of the present invention are concerned, valve 31 may be omitted because valve 41 can be opened by suction and serve the same purpose, therefore, as present valve 31. In other words, valve 41 in such modified form of construction would serve a double purpose, that is, as an automatic suction valve and also as a mechanical unloading valve.

I have described what I believe to be the best form of my invention. I do not wish, however, to be confined to the embodiment shown, but what I desire to cover by Letters Patent is set forth in the appended claims.

I claim:

1. In a compressor, a cylinder, a crankcase for supporting the cylinder, a crankshaft in the crankcase and extending through one end thereof, a piston operated by the crankshaft within the cylinder, said cylinder having the usual automatic intake and outlet valve mechanisms, an unloading valve in the cylinder and operable to prevent compression in said cylinder while the valve is open, an eccentric on the projected end of the crankshaft, a transversely-extending member on the eccentric means responsive to the rotation of said eccentric for oscillating said transverse member, linkage means extending between the transverse member and the unloading valve for effecting the operation of said unloading valve, and hand-adjusting means connected with the transverse member to adjust the same on the eccentric whereby to vary the phase relationship between the operation of the unloading valve and the stroke cycle of the piston.

2. In a compressor, a cylinder, a piston reciprocable in the cylinder, a crankcase on which the cylinder is mounted, a crankshaft within the crankcase and projecting laterally from one end thereof, automatic inlet and outlet valve mech-

anisms, an unloading valve for the compression chamber, means for operating the unloading valve comprising an eccentric on the crankshaft, a transversely-extending member on the eccentric to be operated by the same, an oscillating type cam pivoted on the compressor and having lower and raised cam face portions, and a link connected between the transverse member and the oscillating cam to transmit the oscillating movement of the transverse member to the cam, roller means operable upon the cam surface for imparting movement from the cam to the unloading valve, and means for adjusting the phase relationship between the cam and the stroke cycle of the piston, including a hand lever connected with the transverse member on the eccentric and adapted to alter the oscillatory cam so that the roller means may be affected by either the lower portion or the raised portion of the cam face or by both.

3. A compressor comprising a cylinder having inlet and outlet valves, a shaft, a piston reciprocable in the cylinder by rotation of said shaft, an unloading valve at the closed end of said cylinder adapted to prevent compression in the cylinder while the same is open, means for operating said unloading valve comprising a cam, a member supported on said shaft, means responsive to the rotation of said shaft for oscillating said member about said shaft, and a connection between said member and said cam for oscillating said cam, and means for adjusting the angular position of said member with respect to the stroke phase of said piston to vary the phase relationship between said cam and the stroke cycle.

4. A compressor as described in claim 3, in which said means for oscillating said member about said shaft includes an eccentric affixed to said shaft and embraced by said member with a rotative fit, and a pivot support for said member spaced from said shaft.

5. A compressor as described in claim 3, in which said means for oscillating said member about said shaft includes a pivot support for said member spaced from said shaft, and said adjusting means operates to adjust the position of said pivot support.

6. A compressor as described in claim 3, in which said means for oscillating said member about said shaft includes an eccentric affixed to said shaft and embraced by said member with a rotative fit, and a pivot support for said member spaced from said shaft, and said adjusting means operates to adjust the position of said pivot support.

7. A compressor as described in claim 3, in which said adjusting means comprises a lever journaled for adjusting movement about said shaft.

8. A compressor as described in claim 3, in which said means for oscillating said member about said shaft includes an eccentric affixed to said shaft and embraced by said member with a rotative fit, and said adjusting means comprises a lever journaled on said shaft for angular adjustment thereabout.

9. A compressor comprising a cylinder having inlet and outlet valves, a shaft, a piston reciprocable in the cylinder by the rotation of said shaft, an unloading valve at the closed end of said cylinder adapted to prevent compression in the cylinder, while the same is open, means for operating said unloading valve comprising a cam, an eccentric affixed to said shaft for rotation there-

7
 with, a transverse member embracing said eccentric with a rotative fit, a linkage between one end of said transverse member and said cam for oscillating said cam, and a pivot support for the other end of said transverse member, and means for adjusting the angular position of said member with respect to the stroke phase of said piston by varying the position of said pivot support to vary the phase relationship between said cam and the stroke cycle.

10. A compressor comprising a cylinder having inlet and outlet valves, a shaft, a piston reciprocable in the cylinder by rotation of said shaft, means for selectively changing the effective volumetric displacement of said cylinder, comprising an unloading valve at the closed end of said cylinder adapted to prevent compression while said valve is open, a cam, means for operating said cam, means responsive to the operation of said cam for controlling the operation of said

5 valve to hold said valve open during a selected part of the compression stroke of said piston, a lever journaled for adjusting movement about said shaft, and means responsive to the angular movement of said lever about said shaft for varying the phase relationship between said cam and the stroke cycle of said piston.
